DESIGN FOR AN EVENING GOWN

Harry Berman, New York, N. Y.

Application February 20, 1940, Serial No. 90,371

Term of patent 3½ years

To all whom it may concern:

Be it known that I, Harry Berman, a citizen of the United States and residing in the Borough of Manhattan, in the city, county, and State of New York, have invented a new, original, and ornamental Design for an Evening Gown, of which the following is a specification, reference being had to the accompanying drawing, forming part thereof, wherein:

Fig. 1 is a front view of an evening gown showing my new design.

Fig. 2 is a rear view thereof.

I claim:

The ornamental design for an evening gown, substantially as shown.

HARRY BERMAN.
